Fig. 1

Fig. 4

Fig 2Fig 3

FIG. 1 is a front perspective view taken from the top of a bathtub showing my new design;

FIG. 2 is a top plan view thereof;

FIG. 3 is a front elevational view thereof; and

FIG. 4 is an end elevational view thereof.

The characteristic features of my design reside in the configuration of the front panel and well as shown.

This is a continuation-in-part of design applications Ser. Nos. D. 17,294 and D. 18,771 filed May 3, 1969 and Aug. 20, 1969, respectively.

I claim:

The ornamental design for a bathtub, as shown and described.
